UNITED STATES PATENT OFFICE.

HJALTI S. ANDERSON, OF CYPRESS RIVER, MANITOBA, CANADA.

SHEAF-SHOCKER.

1,311,484.

Specification of Letters Patent. Patented July 29, 1919.

Application filed May 31, 1918. Serial No. 237,565.

To all whom it may concern:

Be it known that I, HJALTI S. ANDERSON, subject of the King of Great Britain, and resident of the town of Cypress River, in the Province of Manitoba, in the Dominion of Canada, have invented certain new and useful Improvements in Sheaf-Shockers, of which the following is a specification.

This invention relates to improvements in sheaf shockers, and the objects of the invention are to facilitate automatically and mechanically forming the sheaves as they are delivered from the binder deck into shocks, to permit of the shock forming mechanism being constructed, so that during the dumping of the shock it will not impact with and cause the shock to inadvertently fail, to provide means whereby the shock forming element may be attached to binders at present in use, and generally to adapt the several parts to better perform the functions required of them.

With the above and other objects in view, the invention consists essentially of the improved construction particularly described and set forth in the following specification and accompanying drawings forming part of the same.

In the drawings,

Fig. 1 is a fragmentary end elevation of a binder showing the improved shocker attached thereto.

Fig. 2 is a plan view of the same.

Fig. 3 is a side elevation of the improved shocker, part being in section.

Fig. 4 is a perspective view of the sheaf collecting basket as seen when closed.

Fig. 5 is a perspective view of the sheaf collecting basket, part being broken away and in section and showing the opposite end to that illustrated in Fig. 4.

Fig. 6 is a fragmentary side elevation of part of the frame of the shocker showing the gear drive thereon.

Fig. 7 is a transverse section through the sheaf collecting basket showing the doors on the large end thereof open.

Fig. 8 is a perspective view of a catch adapted to secure the split portions of the side tracks together.

Fig. 9 is a transverse section through one of the side tracks.

Fig. 10 is a fragmentary sectional view of

a part of the shocker frame, showing the means for operating the doors on the large end of the sheaf collecting basket, and also for actuating the doors on the lower side of the basket.

Like characters of reference refer to like parts in the several figures.

Referring to the drawings A represents a binder of any usual description, and B the shocking mechanism located stubbleward of the binder deck 10 and connected to the frame 11 of the binder by the stays 12, which form with the said frame ball and socket joints, so that when the machine is passing over uneven ground the shocker mechanism will be allowed to move relatively to the binder and thus jarring will not take place in the mechanism.

The shocker mechanism B comprises a pair of spaced side tracks 13, arranged in parallel relation and formed substantially oval in shape, the upper and lower walls being angularly disposed and converging toward the rear end, while the front and rear ends 14 and 15 are substantially curvilinear.

The rear end 15 of each track is formed of two hinged sections 16 and 17, the former of which is connected to the lower wall of the track by the hinge 9, while the latter is connected to the portions 16 by the hinge 18.

The upper end of each portion 17 is provided with a lateral pin 19 designed to extend through the slot 20 in the side plate 21, which is rigidly attached to the major portion of the tracks 13, and in the lower end of the said slot a spring 22 is located, with which the pin engages when the rear portion of the track is lowered.

Each portion 16 of the track 13 is provided with a lateral pin 23 which passes through the curvilinear slot 24 in the lower end of the plate 21, and this pin is adapted to coact with the spring 25 located in the lower end of the curvilinear slot, when the portion 16 of the track has been lowered into the position shown by the dotted lines 100 in Fig. 3.

It will be understood that each track carries a plate 21 rigidly attached thereto.

Each portion 17 of the track carries a downwardly extending spindle 26 on the lower end of which a roller 27 is rotatably

mounted and these spindles are capable of movement vertically, and to eliminate jarring between the rollers and the track a spiral spring 28 is coiled around each spindle, so that the upward movement of the spindle is retarded by the cushioning effect of the spring.

The shocker B is supported intermediate of its length by the axle 29 on the outer end 10 of which a ground wheel 30 is mounted, and on this axle a gear 31 is rotatably mounted and provided with a clutch portion 32 on the boss designed to coact with the clutch portion 33 slidably mounted on the said 15 axle. The clutch portions are under certain circumstances pressed into engagement by the spiral spring 34.

The clutch portion 33 is provided with an annular groove, with which the lower 20 end of the pivoted lever 35 engages, the said lever being offset intermediate of its length and terminating at the free end with a hand grip 36 located adjacent to the driver's seat.

As this lever is manually rotated about its 25 pivoted point, it disengages the clutch portions 32 and 33, which are reengaged when the lever is released.

The gear 31 meshes with the gear 38 carried by the rotatably supported spindle 39, which is provided on the inner end with a sprocket 40 adapted to be connected through the chain 41 with the sprocket 42 rotatably mounted on the non-rotatable shaft 43, extending 35 transversely across the forward end of the track 13 of the shocker B and suitably journaled thereon.

The sprocket 42 is rigidly connected to the wheel 44 provided with spaced peripheral 40 teeth 45, the objects of which will be made clear hereafter.

The tracks 13 are substantially tubular in cross section as shown in Fig. 9 and are adapted to support a pair of collector baskets 46 which are formed substantially like a frustum of a cone, and provided at the ends with yokes 47 carrying rollers 48 which run in the said tubular tracks.

The baskets 46 are each provided with a 50 pair of outwardly opening doors 48^a forming substantially one-half of the side wall of the basket, and one-quarter 49 of the outer wall of the basket is rigid, or non-movable, while adjacent to the rigid wall is 55 an outwardly opening door 50 formed of one-quarter of the side wall of the basket.

In the interior of the basket 46 a plate 51 is located and carried by the rod 52 adjustably mounted in the smaller end wall 53 of 60 the basket, which rod is provided with a collar 54 and thumb-screw whereby the position of the said plate may be altered.

A lever 55 is pivotally mounted intermediate of its length to the end wall 53 and is 65 provided at the ends with eyelets 56 and 57

connected to the links 58 and 59 which are hinged to the doors 48^a of the basket, while intermediate of the pivotal point of the lever and one end, a rod 60 is attached which carries a roller 61 on the outer end thereof adapted to engage with the inclosed bracket 78^a.

The doors 48^a are normally held closed by means of the tension springs 62 which hold the lever 55 and links 58 and 59 in a 75 predetermined position, so that the lever must be moved from this position before the doors 48^a will be closed.

On the yoke 47 at the small end of the basket 46 a downwardly extending catch 80 member 63 is provided.

A pair of doors 64 are hinged intermediate of their length to the frame and at the large end of the basket, and these doors are each provided at one end with a curvilinear race 65 with which rollers on the ends of the transverse arm 66 of the T-shaped rod 67 are adapted to engage.

This T-shaped rod 67 is slidably mounted in a bracket 68 secured to the frame of the 90 basket, and the upper end 69 of the rod is offset and connected by a spring 70 to the basket.

The doors 64 are adapted to slide over each other, so that when the rod 67 is moved 95 the doors will pivot around their hinged points and uncover the large end of the basket.

The means which I provide for actuating the rod 67 consists of a chain 71 connected at one end to the transverse arm 66 of the rod 67, the said chain passing around a guide pulley 72 and thence between a pair of guide rollers 73 connected by the rod 74 with a sprocket 75 which is rotatably mounted on 105 the hinged rod of the door 48^a. The chain after passing between the rollers 73 passes over the sprocket 75 and then around the guide pulley 76, when the free end of the chain is connected to one end of the angle 110 rod 77, the offset end of which is adapted to coact with an adjustable bracket 78 secured to one of the plates 21 on the track 13.

The rod 77 is slidably supported by the arms 79 which are rigidly secured to the 115 hinged rod of the door 48^a.

This door is provided on the outer face with a pair of cam races 80, one of which is adapted to engage with a cam 81 carried by a transversely extending rod 82 extending between the side plates 21 mounted on the track 13 of the shocker, and this cam is adapted to open the door 50, so that the basket collector will be in a position to receive sheaves when it comes opposite the binder 125 deck.

The other cam race 80 is adapted to engage with the cam 83, which depends downwardly from the non-rotatable shaft 43 and this cam is designed to close the door 50 130

after the desired number of sheaves have been delivered to the basket collector 46 to form a proper shock.

When the basket collector 46 has been filled with the desired number of sheaves, the driver releases the lever 35 to allow the clutch portions 32 and 33 to engage and so transmit motion from the axle to the gear 31 which in turn rotates the gear 38 thus 10 rotating the sprocket 40, which through the chain 41 rotates the large sprocket 42.

The motion of the sprocket 42 is transmitted to the wheel 44 which engages with the offset ends of the yoke 47 on the large 15 end of the basket 46, so that the basket will now travel around the front curvilinear end 14 of the tracks 13, and during this motion the cam 83 coacting with one of the cam races 80 closes the door 50 of the basket collector.

When the basket collector 46 is carried to the upper wall of the side track 13 it will gravitate toward the rear of the said track 13, and during this motion the offset catch 25 63 engages with the laterally extending pin 84 of the pivotally supported latch 85, which is journaled intermediate of its length in the bracket 86 mounted on the upper end of the rear portion 17 of the said track.

30 The ends of the latch member 85 are offset and one end 87 is adapted to pass through an orifice in the major portion of the side track 13 to hold the hinged portions 16 and 17 to the side track in elevated position but when the catch 63 engages the pin 84 it disengages the end 87 from the major portion of the side track 13, so that the hinged portions 16 and 17 will rotate slightly about their hinged ends and be lowered into the position shown by the dotted lines in Fig. 3 in which the rollers 27 engage the ground.

It will be seen that the basket 46 on reaching the rear end of the track will assume a 45 vertical position and be maintained in such position by the hook 88 of the latch 85, which engages with the offset ends of the yoke 47 on the smaller end of the basket.

The basket is now positioned for dumping and during the period in which it is being lowered into the position shown by the dotted lines in Fig. 3 the offset end of the rod 77 engages with the bracket 78 transmitting a pull to the chain 71 which in 50 sequence moves the T-shaped rod 67 to open the doors 64.

It should be particularly noted that the sprocket 75 which is connected to the rod 74 carrying the rollers 73 will cause the rollers to travel through a relatively large arc, so that a quick motion will be transmitted to the chain 71 and consequently to the T-shaped rod 67 and doors 64.

Simultaneously with this opening of the 65 doors 64, the doors 48^a are opened by the

roller 61 engaging with the inclined bracket 78^a, so rotating the lever 55 in a clockwise direction and thus swinging the links 58 and 59 outwardly to open the doors 48^a rearwardly.

This leaves the basket collector open to dump the shock.

When the portions 16 and 17 of the track are in lowered position the pins 19 and 23 engage with the springs 22 and 25 and so 75 prevent the said portions of the track jarring.

When the basket collector has been dumped, it is necessary to close the track 13, and this is accomplished by transmitting 80 a pull to a flexible member 89, which passes around the guide rollers 90 in the side plate 21 and is connected to the catch member 85, so that the tension applied to this flexible member will pull the rear end 17 of the track 85 13 upwardly, and the pins 19 and 23 will travel in the slots 20 and 24.

When the track 13 is closed the end 87 of the latch 85 will pass through the orifice in the major part of the track 13, and so close 90 the track.

During this upward pull of the portions 16 and 17 of the track the hook end 88 becomes disengaged from the offset ends of the yoke 47 on the smaller end of the basket 95 46, and the motion transmitted to the portions 17 of the track, disengage the bracket 78 from the rod 77 and roller 61, so that when the track 13 is closed the basket 46 will travel downwardly under gravity until 100 it engages with the lower arm of the major portion of the track 13, when it is fed by gravity toward the wheel 44, and positioned to receive sheaves from the binder deck.

It will be understood that there are two 105 baskets carried by the shocker, so that as one is being dumped, the other is being filled, and thus a continuous collecting of the sheaves and a dumping of the shocks formed, will be carried out.

As many changes could be made in the above construction and many apparently widely different embodiments of my invention within the scope of the claims, constructed, without departing from the spirit 115 or scope thereof, it is intended that all matter contained in the accompanying specification and drawings shall be interpreted as illustrative and not in a limiting sense.

What I claim as my invention is:

1. A shocker consisting of a frame, comprising a pair of spaced endless tracks in a vertical plane, a plurality of collector baskets carried by the tracks with freedom to move therearound, doors on the end and side of the baskets, and means for simultaneously opening the said doors to dump the baskets.

2. A shocker comprising a frame, consisting of a pair of spaced tracks in a vertical 130

4
plane, each track being sectional toward the rear end, a collector basket mounted on the tracks with freedom to travel therearound, means for lowering the sectional rear end of the track when the basket collector is engaged therewith to dump the contents of the basket, and means for elevating and closing the sectional end of the track subsequent to dumping, whereby the basket is positioned to receive sheaves.

3. A shocker comprising a frame, consisting of a pair of spaced tracks, a basket mounted on the tracks with freedom to travel therearound, a plate adjustably mounted in the basket, a door in the side wall of the basket, cam means for opening and closing the door before and after the reception of a predetermined number of sheaves, and means for dumping the basket at the rear end of the tracks.

4. A shocker comprising a frame, consisting of a pair of spaced tracks in a vertical plane, a conical collector basket mounted on the tracks, a pair of doors on the basket adapted to open outwardly, a lever pivoted on the small end of the basket, links engaging with the lever and the said door, means for actuating the lever, doors on the large end of the basket, means for carrying the basket around the tracks, and means for opening the last said doors simultaneously with the first said doors to dump the sheaves in the basket.

5. A shocker comprising a frame, consisting of a pair of spaced tracks in a vertical plane, a basket carried by the tracks, means for moving the basket around the tracks, a pair of doors on the bottom of the basket, cam races on the doors, a T-bar carrying rollers engaging with the cams, a flexible member connected at one end to the T-bar, a slidably mounted bar connected to the other end of the flexible member, and means for actuating the bar to open the door and dump the sheaves in the basket.

6. A shocker comprising a frame, consisting of a pair of spaced endless tracks in a vertical plane, a plurality of baskets carried by the tracks, means for moving the baskets around the tracks, doors on the baskets, cam means for opening the doors, resilient means for controlling the closing of the doors, and means for holding the baskets in a vertical position during dumping.

55 7. A shocker comprising a frame, consisting of a pair of endless tracks in a vertical plane, a plurality of baskets, yokes on the front and rear ends of the baskets adapted to engage with the tracks, doors on the baskets,

and means for opening the doors to dump the sheaves when the baskets are positioned at the rear end of the tracks.

8. A shocker comprising a frame, consisting of a pair of spaced endless tracks having inclined portions, a wheel rotatably mounted at the front end of the frame provided with peripheral projections, baskets carried by the tracks and adapted to be carried around the front end of the tracks by the said wheel and remaining portion of the tracks by gravity, and means for dumping the baskets.

9. A shocker consisting of a frame, comprising a pair of spaced tracks split toward the rear end and having hinged sections, a catch for securing the track in closed position, a basket mounted on the tracks, means for moving the basket around the tracks, a catch on the basket adapted to release the said catch and permit of the hinged sections of the track being lowered, the basket being held by the first catch member in vertical position for dumping, and means for dumping the contents of the basket.

10. A shocker comprising a frame, consisting of a pair of spaced tracks having rear hinged sections, rollers carried by the rear hinged sections, resilient means controlling the upward motion of the rollers, a basket carried by the tracks, means for moving the basket around the tracks, means for normally holding the sections of the tracks closed, means on the basket for releasing the last said means and allowing the hinged sections to be lowered during the dumping of the basket, and means for closing the tracks subsequent to the dumping of the basket.

11. A shocker comprising a frame, consisting of a pair of spaced tracks having rear hinged sections, plates carried by the major part of the track provided with slots, pins on the hinged sections engaging the slots, springs coating with the pins, means for normally maintaining the tracks closed, a basket on the tracks, means on the basket for actuating the said means to lower the hinged section of the track, the first said means being adapted to maintain the basket in a vertical position preparatory to dumping, means for dumping the basket, and means for closing the tracks and releasing the basket, as and for the purposes specified.

In witness whereof I have hereunto set my hand in the presence of a witness.

HJALTI S. ANDERSON.

Witness:

JAMES MITCHELL.
